UNITED STATES PATENT OFFICE

2,488,281

FIRE ALARM SWITCH

Joseph E. Formanek, Britt, Iowa

Application January 30, 1947, Serial No. 725,213

1 Claim. (Cl. 260—140)

1

The present invention relates to a fire alarm switch and it consists in the combinations, constructions and arrangements of parts herein described and claimed.

The invention contemplates the provision of an apparatus including a multiple wafer thermostat adapted to move a lever in response to variations in temperature and a pair of adjustable connections adapted to come into contact with the lever one at a certain selected high temperature and the other at a like selected low temperature.

It is accordingly an object of the invention to provide, in a device of this character, a fire and temperature alarm having means for sounding an alarm at a certain high and at a certain low preselected temperature.

A further object of the invention is the provision of a single thermostat for accomplishing the above-mentioned object.

A further object of the invention is the provision of a device of this character having a minimum number of parts and which will be inexpensive to manufacture yet will be reliable in operation and easily adjusted.

A further object of the invention is the provision of a simple means whereby the aforementioned high and low temperature contacts may be readily and minutely adjusted.

Other and further objects of the invention will become apparent from a reading of the following specification taken in conjunction with the appended drawings, in which:

Figure 1 is a plan view of an embodiment of the invention.

Figure 2 is an end elevational view of the device shown in Figure 1, and

Figure 3 is a side elevational view of the device shown in Figure 1 together with a schematic showing of the circuit employed.

Referring more particularly to the drawings, there is shown therein a frame having a bottom 10, sides 11 and 12 and top end pieces 13 and 14. A brace member 15 is mounted centrally between the sides 11 and 12 and is preferably formed of bakelite or other dielectric material. A second brace member 16 is likewise mounted adjacent to end 13 of the frame and carries centrally thereof a stud 17 to which is affixed a multiple wafer type thermostat 18 which is adapted to bear against the lower end 19 of a bell crank lever which is pivotally mounted in the brace 15 as indicated at 20 and whose upper end 21 projects substantially vertically above

2

the top of the frame. A conical spring 22 is centrally mounted upon the brace 15 and has its smaller end in contact with the lower end of the bell crank lever.

5 The end piece 13 is formed with an upwardly projecting ear 23 in which is threaded a screw 24 having an operating handle 25 and the end piece 14 is provided with a like ear 26 in which is threaded a screw 27 having an operating handle 28. The stud 17 is electrically connected with one end of a circuit as indicated at 29 and the frame is grounded with the other end of the circuit as indicated at 30.

In operation it will be apparent that the screws 15 24 and 27 may be adjusted to make contact with the upper end 21 of the bell crank lever 20 for preselected high and low temperatures, respectively. Upon a rise in temperature the thermostat 18 will expand moving the lower end 19 of the bell crank lever 20 against the action of the spring 22 thereby causing eventually contact to be made between the screw 24 and the upper end 21 of the bell crank lever 20. This will complete an electrical circuit including the screw 24, the entire bell crank lever 20, the thermostat 18, the stud 17, the connector 29, the source of power 31, an alarm bell 32, and the frame (through contact 30) and thence back to the screw 24. This will complete a circuit through the alarm 32, as above stated, and thus sound the same when a preselected high temperature has been reached.

It will be apparent then, that upon a preselected low temperature having been reached, the thermostat 18 will have contracted sufficiently for the spring 22 to urge the bell crank lever 20 into contact with the screw 27 whereupon the circuit above mentioned with the exception that the screw 27 is now included instead of the screw 24 will be completed and the alarm 32 sounded.

While but one form of the invention has been shown and described herein, it will be readily apparent to those skilled in the art that many minor modifications may be made therein without departing from the spirit of the invention or the scope of the appended claim.

What is claimed is:

50 A thermostatic device adapted to close an electric circuit comprising a metal frame having top, bottom, end pieces, projections having threaded openings and extending upwardly from said end pieces, adjusting screws threaded through said openings and serving as contacts, the frame being adapted to carry a current, an insulating

member secured within the frame to the top and bottom pieces, a second insulating member disposed in the frame adjacent one end thereof, a wafer type thermostatic element anchored to the second insulating member, a contact terminal engaging with the element and adapted to have a wire connected with it, a lever pivoted on the first mentioned member and having a lower arm extending into engagement with the thermostatic element and an upper arm extending upwardly from the top of the frame to between the ends of said contact screws for engaging either of the same depending upon the contraction and expansion of the thermostatic element, and biasing means on the first mentioned insulating member engaging the lower arm of the lever urging the same into engagement with the thermostatic element.
